CHANGE DISPENSING MECHANISM

Jack F. Eierman, Wauwatosa, Wis.

Application August 20, 1947, Serial No. 769,620

4 Claims. (Cl. 194—10)

1

My invention relates to automatic change mechanism for coin operated vending machines and the like.

One object of my invention is to provide a simple and durable automatic change mechanism relatively free of service problems.

A further object is to provide change mechanism which is positive acting throughout its entire operating cycle.

This and other inherent objects are disclosed in the preferred embodiment of my invention, as described in the annexed specifications and drawings, in which:

Fig. 1 is a schematic diagram illustrating the electrical circuit of the illustrated embodiment of my invention, schematically depicting some of the mechanical structure;

Fig. 2 is a top plan view of the coin receiving tubes of the changer showing some of the operating mechanism;

Fig. 3 is a front elevational view of the structure illustrated in Fig. 2 with some of the parts shown in cross sectional view for clarity;

Fig. 4 is a side elevational view illustrating the right side of the structure shown in Fig. 3, with some of the parts shown in cross-sectional view for clarity;

Fig. 5 is a detailed cross-sectional view of the line 5—5 of Fig. 4;

Fig. 6 is a detailed perspective view of a lost motion switch actuator used to control the slide return part of the operating cycle of the machine;

Fig. 7 is a schematic exploded view of portions of the structure illustrated in Fig. 5 showing the mechanism ready for the commencement of an operating cycle;

Fig. 8 is similar to Fig. 7 but shows the mechanism ejecting one nickel;

Fig. 9 is similar to Fig. 7 but shows the mechanism ejecting two nickels and one dime; and

Fig. 10 is a line diagram of the electrical circuit shown in Fig. 1.

The selected embodiment of my invention includes a plurality of change tubes 10, 11, and 12, the change tube 10 for example being provided for quarters, 11 for dimes, and 12 for nickels. These change tubes are preferably of metal and are open at each end. The lower end of each of the tubes is mounted in a hole 14 in a horizontal plate 15 of the frame of the machine in any desired manner such as by welded joints 16 (Fig. 5).

Adjacent and below that portion of the plate 15 which supports the change tubes, there are mounted two coin slides 17 and 18 (Figs. 5, 7, 8

2

and 9). Beneath the coin ejecting slides 17 and 18 the frame 15 is provided with a stationary bottom plate 19, the sides of which embrace the sides of the slides 17 and 18 and the plate 18, so as to form a slot permitting the reciprocation of slides 17 and 18.

The lower coin ejecting slide is provided with a coin receiving hole 20 and the upper coin ejecting slide 18 is provided with coin receiving holes 21 and 22. When the machine is ready to commence a cycle of operation the holes 20 and 21 are in alignment with the bore of the change tube 12 and the hole 22 is in alignment with the bore of the change tube 11. The coin ejecting slide 18 is offset as at 23. The left hand part of slide 18 overlies the coin ejecting slide 17, and, beyond the offset 23, the right hand side of the slide 18 is in axial alignment with the coin ejecting slide 17. A stationary spacer 24 is provided between the right hand portion of the slide 18 and the lower surface of the plate 15 so as to maintain proper alignment of the slide 18.

Slide 17 and the lefthand portion of slide 18, both of which are located beneath the change tube 12, have a thickness each equal to the thickness of a nickel, and the right hand portion of slide 18 beneath the change tube 11 has a thickness equal to the thickness of a dime. Two coin discharging openings 25 and 26 are provided in the stationary bottom plate 19, the opening 25 being provided for the discharge of nickels and the opening 26 being provided for the discharge of dimes.

If the coin tubes 11 and 12 are provided with dimes and nickels respectively one dime will nest in the opening 22 in slide 18 and one nickel will rest in each of the openings 23 and 24 in the slides 17 and 18 respectively. If the slide 17 then be moved to the left and the slide 18 be maintained stationary, then the nickel carried by slide 20 will be moved to the left until it registers with opening 25 (Fig. 8). The nickel will then be discharged through the coin discharge opening 25. When the slide 17 is returned to its initial operating position (Figs. 5 and 7) the opening 20 will again be aligned with the opening 21 and the bore of the tube 12, permitting the nickel resting in opening 21 to drop down to the opening 20 and permitting the opening 21 to be re-filled from the coin tube 12.

If the slide 18 be moved to the left, the offset portion 23 will contact the right end of the slide 17 and slides 17 and 18 will thereby be moved to the left as a unit until the opening 22 registers with the coin discharge opening 26 and the open-

ings 20 and 21 register with the coin discharge opening 25 (Fig. 9). In this position of the machine the dime carried by opening 22 will be discharged through the discharge opening 26 and the two nickels carried by openings 20 and 21 will be discharged through the coin discharge opening 25, thereby furnishing 20 cents change.

If the slide 17 be now returned to the right, the right hand portion of the slide will abut the offset 23 in the slide 18 and will carry both slides back to their normal position (Fig. 7).

The foregoing structure illustrates the general environment of the applicant's invention. The invention, which is described hereinafter, relates to the new and improved mechanism for causing the coin changing machine to go through the foregoing operating cycle.

The slides 17 and 18 are moved to and fro by a plurality of solenoids 27, 28 and 29, provided with cores, 30, 31, and 32 respectively. The core 30 is secured in any desired fashion to the slide 18 to move the slide 18 to the left and the core 32 to the slide 17 to move the slide 17 to the right.

The electric circuit for operating the machine (Fig. 1) includes a pair of limit switches 33 and 34 arranged respectively near the bottoms of the change tubes 11 and 12. These limit switches 33 and 34 are provided with operating fingers 35 and 36 respectively. As soon as the coin tubes 11 and 12 are provided with sufficient coins to enable the machine to make change, the coins will contact the operating fingers 35 and 36 thereby closing switches 33 and 34 to condition the machine for operation.

Since coin changing devices such as that disclosed herein are ordinarily used in vending machines, a limit switch 37 is provided which closes when the vending machine is provided with merchandise to be vended but which opens when the vending machine is empty.

The electric power for the machine is supplied through power terminals 38 and 39. Output terminals 40 and 41 are provided to furnish the operating current to conventional dispensing mechanism in any desired dispensing machine.

Assuming that a nickel is placed in a coin slot leading to change tube 12 and that the dispensing machine is not empty so that limit switch 37 is closed, the coin is accepted or rejected by proven slug ejection means such as 42 (Fig. 4). If the coin passes conventional slug rejecters, it closes the contacts of switch 43 operated by an operating trip 44a located in the path of the travel of the coin. Parenthetically, a similar operating trip is mounted above each of the tubes 12, 11 and 10 as elements 44(a), 44(b), and 44(c) respectively. A gate 45(a) is arranged in any desired fashion beyond trip 44(a) so that when the coin strikes the gate it tends to rotate it in a clockwise direction (Fig. 4). The gate 45(a) is normally prevented from rotating in a counter-clockwise direction by a mechanical interlock 46(a), which is connected to the core 47 of a solenoid 48. When the contacts of switch 43 are closed, by the passage of a coin, a circuit is closed comprising power terminal 38, switch 37, switch 43, solenoid 48 and power terminal 38. This energizes the solenoid 48 thereby withdrawing the mechanical interlock 46(a) from operative engagement with the gate 45(a) thereby permitting the coin to drop down chute 49(a) (Fig. 4). If, however, switch points 37 are opened because the vending machine is empty, then the mechanical interlock will not be withdrawn and

the coin will be discharged through path 50(a) to a coin return slot.

Assuming that the coin has traveled down chute 49(a), it will contact operating finger 51(a), thereby closing switch 52 mechanically operated by finger 51(a). This makes a circuit comprising the power terminal 38, the switch 52, output terminal 41, output terminal 40 and power terminal 39 thereby initiating the operation of the vending machine connected to output terminals 40 and 41. It will be observed that for the nickel operating cycle no change is ejected, it being assumed for the purposes of illustration that the value of the article being vended by the vending machine is five cents whereby a purchaser will be entitled to no change.

Assuming that a dime is placed in a coin slot leading to change tube 11, that the dispensing machine is not empty so that limit switch 37 is closed, that there are sufficient nickels in coin tube 12 to close limit switch 34, the coin is accepted or rejected by proven slug rejection means. If the coin passes the conventional slug rejecters, it contacts an operating trip 44(b) located in the path of the travel of the coin in the same manner as trip 44(a) in the nickel change tube. The operating trip 44(b) closes the contacts of a switch 53. The closing of the contacts of the switch 53 closes a circuit comprising power terminal 38, switch 37, switch 34, switch 53, solenoid 46 and power terminal 38 thereby energizing the solenoid 46 to withdrawn the mechanical interlock 46(b) from operative engagement with the gate 45(b) in the same fashion as in the case of the nickel slot. This permits the coin to drop down chute 49(b). If, however, switch points 37 are open because the vending machine is empty, or if limit switch 34 is open because there are no nickels in the nickel tube, then the mechanical interlock will not be withdrawn and the coin will be discharged through path 50(b) to a coin return slot.

Assuming that the coin has traveled down chute 49(b) it will contact operating finger 51(b) thereby closing a switch 54 mechanically operated by finger 51(b). This will close a circuit comprising power terminal 38, solenoid 28, switch 54, output terminal 41, output terminal 40 and power terminal 39 thereby simultaneously initiating operation of the vending machine and energizing the solenoid 28. The energization of the solenoid 28 moves the core 31 to the left (Fig. 5) thereby moving coin slide 17 to the left. Moving coin slide 17 to the left moves the nickel carried in opening 28 over to the coin discharge opening 25 (Fig. 8) thereby giving the purchaser five cents change. Thus, a purchaser receives a five cent article and five cents in change for his dime.

Means are also provided for returning the operating parts of the machine to their initial position for the commencement of a new cycle. A trigger 55 (Figs. 3 and 6) is mechanically connected to the core 31 so that movement of the core 31 to the left carries trigger 55 to the left. The trigger 55 extends downwardly into a slot 56 in a slide 57. The slide 57 is mounted for to and fro movement in a frame 58 secured to the framework of the machine. As the trigger 55 moves to the left it will contact the left end of the slot 56 to move the slide 57 to the left (Fig. 3). Slide 57 then contacts the operating finger 59 of a normally open switch 60 thereby closing a circuit comprising power terminal 38, switch 60, solenoid 29 and power terminal 38 (Figs. 1 and

10). This energizes the solenoid 29, moving the core 32 to the right and carrying the coin ejecting slide 17 back to its initial position. The trigger 55 will be moved to the right in the slot 56 until it contacts the right end of the slot 56 thereby moving the slide 57 to the right (Figs. 3 and 6). This permits the operating finger 53 of the switch 60 to return to its normal position to permit switch 60 to open thus de-energizing the solenoid 29.

The lost motion switch operator comprising the trigger 55, the slot 56, the slide 57 and the frame 53 is provided with a friction device to prevent too easy movement of the slide 57. This friction device comprises a friction member 61 which is urged against the lower surface of the slide 57 by a spring 62 which bears against a nut 63. The nut 63 is threaded upon a screw 64 secured to the lower surface of the friction member 61 and the bottom of the spring 62 is carried by the frame 53 of the lost motion device. The amount of friction between the friction member 61 and the slide 57 may be adjusted with the nut 63.

Assume that a quarter is placed in a coin slot leading to change tube 10, and that the coin is accepted or rejected by proven slug ejection means such as 42. If the coin passes conventional slug ejectors, it closes the contacts of switch 65 operated by an operating trip 44(c) located in the path of the travel of the coin. If the dispensing machine is not empty so that the limit switch 37 is closed, if there are nickels in the nickel tube so that limit switch 34 is closed, and if there are dimes in the dime tube 11 so that limit switch 33 is closed, a circuit is made comprising the power terminal 39, switch 37, switch 34, switch 63, switch 65, solenoid 48 and power terminal 38. This energizes the solenoid 48 thereby withdrawing the mechanical interlock 46(c) from operative engagement with the gate 45(c) thereby permitting the coin to drop down chute 49(c). If, however, switch points 37 are open because the vending machine is empty, or switch 34 is open because there are no nickels in the nickel tube, or switch 33 is open because there are no dimes in the dime tube, then the mechanical interlock will not be withdrawn and the coin will be discharged through path 50(c) to a coin return slot.

Assuming that the coin has traveled down chute 49(c), it will contact operating finger 51(c) thereby closing switch 66 mechanically operated by the finger 51(c). This closes a circuit comprising power terminal 38, solenoid 27, switch 66, output terminal 41, output terminal 40 and power terminal 39 thereby simultaneously effecting operation of the vending machine and energization of the solenoid 27. Energization of the solenoid 27 moves its core 30 to the left (Figs. 5 and 9). This carries the slide 18 to the left and the abutment of the offset portion 23 of slide 18 with the right end of slide 17 moves slide 17 to the left (Fig. 8). This discharges two nickels from openings 20 and 21 through discharge opening 25 and discharges a dime from opening 22 through discharge opening 26 thereby giving a purchaser a five cent article and change comprising two nickels and one dime.

In this part of the cycle the lost motion device causes the operation of the switch 60 in the same manner as described for the operation of the dime slot. The movement of slide 17 to the right causes the right end of slide 17 to engage abutment 23 and slide 18 thereby moving all of 75

the operating parts back to their initial position. The opening of switch 60 de-energizes the solenoid 29 thereby permitting the commencement of a new cycle.

It is quite obvious that it is not necessary to use the foregoing mechanism for the exact change arrangements illustrated. A cent and a half dollar tube may be added if the machine is intended to accept coins of such denominations and the thicknesses of the various slides may be altered to handle two to three coins, or even more in the changing operation rather than using the single coin thickness slides depicted. Such modifications need not be described in detail because they are within the skill of any mechanic working in this art.

Further, if the machine is to be used for coin changing purposes exclusively and not in connection with a vending machine the output terminals 40 and 41 and switch 37 may both be bridged. In the selected embodiment of the applicant's invention, this would necessitate a doubling of the thickness of slide 17. In this manner, if a dime is used to operate the machine, the slide 17 will eject two nickels and if a quarter is fed into the machine the slide 18 will eject one dime and one nickel and the slide 17 will eject two nickels thereby giving the operator of the machine his proper change.

Various other modifications and details may be made without departing from the spirit of the invention and the exclusive use of all of such modifications is contemplated, the applicant's invention being defined by the appended claims.

I claim:

1. In a change dispensing mechanism having a plurality of change tubes, and a plurality of change ejecting slides; a solenoid for operating at least one of said change ejecting slides; a solenoid for returning at least one of said change ejecting slides to its normal initial position; and means for operating one of said slides one complete cycle only and for stopping said slide automatically in its normal initial position, said means including an operating circuit to energize the operating solenoid; an electrical return circuit to energize the return solenoid; a lost motion switch operator operated by movement of one of said slides; and a switch operated by movement of said 50 lost motion switch operator to energize said return solenoid operating circuit upon movement of said change ejecting slide to its change ejecting position and operated by return of said change ejecting slide to its normal position to de-energize said return solenoid operating circuit.

2. In a change dispensing mechanism including a change tube and a change ejecting slide; a solenoid for operating said change ejecting slide; a solenoid for returning said change ejecting slide to its normal position; and means for operating said change ejecting slide one complete cycle only and for stopping said slide automatically in its normal position, said means including an operating circuit to energize the operating solenoid; an electrical return circuit to energize the return solenoid; a lost motion switch operator operated by movement of said slide; and a switch operated by movement of said lost motion switch operator to energize said return solenoid operating circuit upon movement of said change ejecting slide to its change ejecting position and operated by return of said change ejecting slide to its normal position to de-energize said return solenoid operating circuit.

3. A change dispensing mechanism including a

7
change tube; a coin ejecting slide having a coin receiving portion, said coin ejecting slide having a first position of movement for receiving a coin from said change tube and a second position of movement for ejecting a coin from said coin receiving portion; a first solenoid for moving said coin ejecting slide from its first position of movement to its second position of movement; a second solenoid for returning said slide from its second position of movement to its first position of movement; and means operable by the insertion of a coin for operating said coin ejecting slide one complete cycle only and for stopping said slide automatically upon the return of said slide to its first position of movement, said means including a coin control switch operated by passage of a coin to initiate operation of said first solenoid; a lost motion switch operator operated by said slide; and a switch operated by said lost motion switch operator to initiate operation of said second solenoid upon movement of said slide to said second position of movement and to de-energize said second solenoid upon movement of said slide to said first position of movement.

4. A change dispensing mechanism including a 25 change tube; a coin ejecting slide having a coin receiving portion; said coin ejecting slide having a full operating cycle comprising a normal position for receiving a coin from said change tube and a second position for ejecting a coin from 30 said coin receiving portion; a first solenoid for moving said coin ejecting slide from its normal position to its second position; a second solenoid for returning said slide from its second position to its normal position; and means for operating said coin ejecting slide one complete cycle only

5
10
and for stopping said slide automatically in its normal position, said means including coin operable means to energize the first solenoid to move the coin ejecting slide from its normal position to its second position and slide operable means actuated by reciprocation of the slide for energizing the second solenoid upon movement of the slide to its second position and for de-energizing the second solenoid upon the return of the slide to its normal position.
